US00D602327S

(12) **United States Design Patent**
Hyde et al.

(10) **Patent No.:** **US D602,327 S**
(45) **Date of Patent:** **** Oct. 20, 2009**

(54) **SMALL SHOULDER PLANE**

779,392 A 1/1905 Bjordal
781,771 A 2/1905 Gardner

(75) Inventors: **Brent K. Hyde**, Ottawa (CA); **Steven K. Jones**, Ottawa (CA); **Terry Saunders**, North Gower (CA); **Brian Ebbinghaus**, Kanata (CA)

(Continued)

(73) Assignee: **Lee Valley Tools, Ltd.**, Ottawa, ON (CA)

CA 554421 3/1958

(**) Term: **14 Years**

(Continued)

(21) Appl. No.: **29/327,660**

OTHER PUBLICATIONS

(22) Filed: **Nov. 11, 2008**

274,600 A	3/1883	Hegglund
296,207 A	4/1884	Mosher et al.
305,603 A	9/1884	Keiser
306,877 A	10/1884	Traut
315,014 A	4/1885	Duncan et al.
316,296 A	4/1885	Rodier
323,804 A	8/1885	Gage
368,003 A	8/1887	Polhemus
383,234 A	5/1888	Millsap
545,732 A	9/1895	Schade
556,835 A	3/1896	Smith
636,830 A	11/1899	Miller
744,411 A	11/1903	Sarasin
749,827 A	1/1904	Sjolander

FIG. 1 is a perspective view of the small shoulder plane of this invention.

FIG. 2 is a right side elevation view of the small shoulder plane shown in FIG. 1; the left side elevation view being a mirror image.

FIG. 3 is a front end elevation view of the small shoulder plane shown in FIG. 1.

FIG. 4 is a back end elevation view of the small shoulder plane shown in FIG. 1.

FIG. 5 is a top plan view of the small shoulder plane shown in FIG. 1; and,

FIG. 6 is bottom plan view of the small shoulder plane shown in FIG. 1.
